UNITED STATES PATENT OFFICE.

GEORGE W. BEADLE, OF BAYONNE, NEW JERSEY, ASSIGNOR TO SINGLE SERVICE PACKAGE CORPORATION OF AMERICA, OF NEW YORK, N. Y., A CORPORATION OF NEW JERSEY.

MACHINE FOR CLOSING PAPER CARTONS.

1,133,425.

Specification of Letters Patent. Patented Mar. 30, 1915.

Application filed November 5, 1912. Serial No. 729,701.

To all whom it may concern:

Be it known that I, GEORGE W. BEADLE, a citizen of the United States, residing at Bayonne, in the county of Hudson and State of New Jersey, have invented certain new and useful Improvements in Machines for Closing Paper Cartons; and I do hereby declare the following to be a full, clear, and exact description of the invention, such as will enable others skilled in the art to which it appertains to make and use the same.

This invention relates to machines for making paper cartons, and especially to that portion of the mechanism of such machines which inserts the closure in the carton body during the process of manufacture, and has for its object to produce a mechanism which will insert disk closures in already formed tubes in a manner more efficient than the mechanisms which have been heretofore proposed.

With this and other objects in view, the invention consists in the novel details of construction and combinations of parts more fully hereinafter disclosed and particularly pointed out in the claims.

This invention is an improvement on the invention described and claimed in my co-pending application #673,084, filed January 30 24, 1912, and entitled "Machine for making paper cartons."

Referring to the accompanying drawings forming a part of this specification, in which like numerals designate like parts in all the views:—Figure 1 is an end elevational view of the general mechanism employed in producing carton bodies from a continuous strip of paper; Fig. 2 is a sectional view illustrating the closure forming and inserting mechanism in its retracted position; Fig. 3 is a like view of said mechanism when it has advanced almost to the point of cutting a paper disk from the paper strip out of which it is formed; Fig. 4 is a view similar to Fig. 2, but showing the parts in their final position after the disk has been formed and inserted in the bottle mouth; Fig. 5 is a sectional plan view taken on the line 5—5 of Fig. 4 looking in the direction of the arrows; Fig. 6 is a sectional view taken on the line 6—6 of Fig. 4 looking in the direction of the arrows; Fig. 7 is a sectional view taken on the line 7—7 of Fig. 6, looking in the di-

rection of the arrow and illustrating only the circular portion of the ring which moves down over the bottle mouth when the closure is being inserted; Fig. 8 is a view of the ring removed from the machine, as seen in a direction opposite from that of the arrows in Fig. 4, and showing the guide rods and guide pieces for the ring in section; Fig. 9 is a diagrammatic view illustrating the various positions of the mandrels during the process of finishing the carton bodies and also showing in end elevation the mechanism for forming grooves in the bottle bodies; Fig. 10 is a side elevational view of the mechanism shown in Fig. 9, for forming grooves in the bottle bodies; Figs. 11, 12 and 13 are sectional views illustrating various steps in the completion of the bottle closure; Fig. 14 is a diagrammatic view of the plunger and bottle mouth showing on an exaggerated scale that the bottle closure is larger than the bottle mouth; Fig. 15 is a plan view of the mandrels for forming the tubes, and of the crimping mechanism coacting with said mandrels for closing the said tubes; and, Fig. 16 is a sectional view of the mechanism shown in Fig. 15.

Referring first to Fig. 1 and to my co-pending application above, it will be understood that the paper strip 2 is unwound from the roller 1, passes through a guide tube 3, is severed by a knife 4 into suitable lengths, paste is suitably applied thereto as at 5, and the severed and paste coated strip is wound upon the mandrel 6, mounted on the revolving carrier 7 secured on the shaft 11. The carrier 7 has associated therewith the gear 8 which meshes with the gear 9, mounted on the shaft 10.

The means for forming the tube illustrated in Fig. 1 form no part of my present invention, and are here only illustrated in order to render clear the operation of the closing mechanism to be described below. However, it should be said that the mechanism illustrated in Fig. 1 is so timed that the various mandrels 6 first receive the paper as there illustrated, wind the same into suitable tubes, and thereupon, as the frame 7 revolves, each mandrel brings its tube to a position where the latter is dried, and then opposite a closing mechanism for inserting disk closures into the already formed and

dried tubes, then in register with a crimping mechanism whereupon the outer edge of the tube is crimped over the disk which has been inserted in said tube, then opposite a grooving mechanism, whereupon an inwardly extending groove is formed in the body of the tube just below the inserted disk to support the same, and finally the said mandrels bring the tubes to a position where they are 10 discharged from the machine, all as is diagrammatically illustrated in Fig. 9.

As further illustrated in my application above, suitably connected with the shaft 10 is a shaft 12 (Fig. 2), which drives the carton closing mechanism constituting my present invention, now to be described.

As is well known, in the closing of paper vessels that are destined to hold liquids, it is essential that an exceedingly tight closure 20 be formed, because otherwise, owing to the nature of the material and the subsequent compression of the liquid filled package during handling, the contents are liable to leak and thereby destroy the efficiency of the 25 package.

In order to provide an exceedingly inexpensive and at the same time, a very efficient closure, I have devised the following mechanism for inserting closures in the mouths of 30 paper bottles which are slightly larger than the interior of said mouths. That is to say, by my machine, disks of paper may be cut out of a diameter say one-thirty-second of an inch larger than the interior diameter of 35 the bottle mouth, and forced into the bottle mouth without raising a bur, and forming exceedingly tight and efficient closures which gives perfect satisfaction in practice.

Referring more particularly to Figs. 2 and 40 3, the paper 13 out of which the closures are formed, is suitably fed from the roll 14 along the channel-way 15 and in the path of the cutting die 16, reciprocated from the shaft 12 by means of the connection 17, all as is 45 fully disclosed in my copending application above. In said application, however, the inserting plunger located on the interior of the cutting die 16 is non-expanding and therefore, of necessity must be of a diameter 50 smaller than the diameter of the cut disk by at least twice the thickness of the walls of the cutting die 16. Such a non-expanding plunger, therefore, would be of a less diameter than the interior of the bottle mouth, 55 and if it is attempted to force a disk into the bottle mouth which is larger than the same, by such a non-expanding plunger, a bur would inevitably form around the edge of said disk on the interior of the bottle mouth, 60 and a bad joint would result. Therefore, my present invention differs, among other features from the former invention, in that the inserting plunger 18 of the present invention is of an expanding type, and as soon as its

extreme outer edge leaves the cutting plunger 65 16, it expands outwardly to the diameter of the interior of the bottle mouth, and thereupon fits the said interior so that no bur is formed on the said disk during the inserting operation, as will appear below.

The paper 13 being fed by the mechanism disclosed in my application above, underneath the cutting plunger 16, the latter moves 70 toward the right, as shown in Figs. 2 and 3, and cuts a disk from said paper which is 75 slightly larger than the interior of the bottle mouth 20. As the shaft 12 continues to revolve, the inserting plunger 18 moves forward. This said plunger may be of any suitable expanding type, but preferably is composed of the spring fingers 21 which are normally somewhat compressed when they are on the inside of the plunger 16, as illustrated in Figs. 2 and 3, but will expand to the full diameter of the interior of the mouth 20, as 85 illustrated in Fig. 4, as soon as they leave the said plunger 16.

Located inside the spring fingers 21 is a solid plunger member 23 provided with a pin 24 projecting therefrom, and controlled 90 by the spring 25. The outer end of the member 23 is further convexly curved, as shown, to fit the concave curved end of the mandrel 6, over which the mouth 20 of the carton 27 fits. The said pin 24 projects slightly beyond the convex surface of the plunger member 23, and therefore as the fingers 21 and member 23 advance, the said pin 24 first contacts with the disk 22 and tilts the same, as diagrammatically illustrated in Figs. 11 95 and 14. In this tilted position, one end of the diameter of the disk rests inside the bottle mouth near the end of the mandrel 6, while the other end of the said diameter is about entering the bottle mouth so that although the disk is slightly larger than the bottle mouth, yet at the same time, it can be 100 accommodated within the same in its inclined position.

It is now evident that if a plunger, such as 110 23, which is smaller than the diameter of the interior of the bottle mouth, should force the disk home, a bur would be raised along the outer edge of the disk and on the interior of the bottle mouth, thereby causing a bad 115 joint, as above stated. However, in my present improvement, the fingers 21 automatically expand to the full size of the interior of the bottle mouth, and thereupon force home the disk, without raising any bur at all. During this further advance of the closing plunger, the pin 24 moves toward the left, 120 as seen in Fig. 4, and against the action of its spring 25, as will be readily understood.

The extreme end of the mandrel 6 being 125 concave, and that of the plunger member 23 being convex, as shown, the disk 22 is seated in a slightly curved condition, which

- 5 further causes the joint between its outer edge and the bottle mouth to be tightened when the liquid contents of the bottle attempt to force the same outwardly.
- 10 The bottle mouth 20 being composed of paper stock, it is evident that the outward pressure of the disk 22 is liable to unduly stretch the same, and thereupon prevent the joint from being as tight as may be desired.
- 15 Accordingly, in order to support the exterior of the mouth 20, I have provided the ring 30, having the guide pieces 31 fitting the interior of the orifice in the plate 32, through which the disk 22 is forced, and 20 adapted to slide outwardly over the bottle mouth from its position shown in Figs. 2 and 3, to its position shown in Fig. 4, as will now be described. Mounted upon the said bed plate 32 and passing through the same, 25 are the guide pins 35 controlled by the springs 36 and provided at one end with the bearing pieces 37 against which a flange of the cutter 16 is adapted to contact during its cutting operation. The other end of the 30 pins 35 fit the ears 39 of the ring member 30, and when this said contact takes place, the said ring member is forced from its normal position, shown in Fig. 3, for example, to its position over the bottle mouth shown 35 in Fig. 4, and thereupon effectually supports the exterior of the bottle mouth and prevents it from being unduly pressed outward during the disk closing operation. After the bottle mouth 20 has thus received its 40 disk, the members 16 and 18 recede into the position shown in Fig. 2, and the said springs 36 return the ring member 30 to its normal position. The bottle body 27 having now been provided with an end closure, the 45 shaft 11 is automatically rotated 60° and the mandrel 6 carrying the closed tube 27 is brought to the crimping position indicated in Fig. 9. The said mandrel 6, as disclosed in my said application above, 50 is of the expanding type, and preferably of the construction shown in Figs. 15 and 16. The mechanism by which the said mandrels are expanded, form no part of the present invention, and therefore, will not be described herein further than to say that 55 through suitable mechanism, the shaft 40 is reciprocated, which, through the wedge members 41, forces outwardly the segments 42, and thereupon hold firmly the carton body 27 against turning. When the said mandrels 6 reach the crimping position, they 60 are in register with the crimped tool 43, which is rapidly turned by means of the gear 44 on the shaft 45, as disclosed below and the extreme edge or mouth 20 of the tube 27 is turned over or crimped in, as illustrated in Figs. 12, 13 and 16. The crimped over edge is chosen of such dimensions that it approximately fits the disk 22,
- but in order to further strengthen the joint 65 thus formed, and also to insure that the disk 22 shall be firmly locked in place, the mandrel 6 is next moved another 60° and carries the closed tube 27 from the crimping position to the grooving position, as indicated in Fig. 9. The mandrels 6 are further provided with the gear 46, which causes the same to rotate upon their axes by the means about to be described.
- 70 At the grooving position, I have provided a grooving tool 47, the edge of which is eccentric to the path of the outer edge of the moving body 27, and intersects the said path to a slight degree, or to an amount equal to the depth of the groove it is desired 75 to form in the said body 27. Accordingly, as the mandrel 6 reaches the said grooving position, a gear 48 (Fig. 10) meshes with the gear 46 on the mandrel, and rapidly rotates the same. That is to say, said gear 48 is mounted upon the shaft 49 carrying the sprocket 50 over which passes the sprocket chain 51, and which chain is driven by the motor 52 provided with a gear 53, which also meshes with the gear 44 driving the 80 shaft 45 and crimping tool 43. The body 27 of the tube being thus rapidly rotating while firmly held by the expanding mandrel 6, and the edge of the tool 47 thus intersecting the path of the said tube 27, a groove 55 of pre-determined depth is formed in the body portion of the tube, as will be clear from 85 Figs. 9, 12 and 13. In order to facilitate the formation of this groove, the mandrel 6 is provided with a groove 56 (Figs. 10 and 12) 90 into which the material of the tube may be forced.
- 95 Since it is often necessary to close tubes 27 of different lengths, I have provided a plurality of grooving tools 47 and have also 100 provided a plurality of grooves, such as 57, 58 and 59 in the mandrel 6 to accommodate the tubes of different lengths. The said tools 47 are adjustable in and out along the 105 slideways 60, and the screws 61 facilitate a 110 still finer adjustment.
- 115 The position of the grooves 56, etc., in the mandrels 6, are so chosen that the groove 55 formed in the tube will be immediately under the disk 22, and will tend to force 120 the same outward against the turned over edge 20 of the bottle mouth, so that the said disk 22 is firmly held between said turned over edge and said inwardly extending groove. It results from this that not only 125 is a joint of unusual tightness produced, but the disk is firmly locked in place against movement in either direction. The groove and turned over edge further serve to greatly strengthen and stiffen the ends of 130 the packages thus formed. A further advantage in this method of closure is the fact that the air may escape through the

expanding mandrel, and therefore no resistance, owing to the pressure of said air, is met with during the disk closing operation.

5. The mechanism is perfectly automatic as will be understood from my copending application above, and after the tubes receive their grooves 55, they are discharged from the machine, when the mandrel is ready for 10 the reception of an additional strip of paper preparatory to the formation of a new tube.

It is obvious that those skilled in the art may vary the arrangement of parts, as well as the details of construction without departing from the spirit of my invention, and therefore I do not wish to be limited to 15 the above disclosure except as may be required by the claims.

What I claim is:—

20 1. In a carton closing apparatus, the combination of a mandrel carrying the carton to be closed; means for supplying to said carton a closure of a slightly larger diameter than the interior of said carton; means 25 for causing said closure to assume an inclined position as it enters said carton; and means of the same diameter as the interior of said carton for forcing said closure inside said carton, substantially as described.

30 2. In a carton closing apparatus, the combination of a mandrel carrying a carton to be closed; a paper supply; a reciprocating cutting plunger adapted to cut closures from said supply slightly larger than the interior 35 of said carton; an expanding closing plunger located inside said cutting plunger adapted to move relatively thereto and to expand to the size of the interior of said carton, while forcing said closure into the 40 latter; and means located inside said expanding plunger for causing said closure to assume an inclined position as it enters the carton mouth, substantially as described.

45 3. In a carton closing apparatus, the combination of a mandrel carrying a carton to be closed; a paper supply; a reciprocating cutting plunger adapted to cut closures from said supply slightly larger than the interior of said carton; an expanding closing 50 plunger located inside said cutting plunger adapted to move relatively thereto and to expand to the size of the interior of said carton, while forcing said closure into the latter; a supporting ring adapted to move 55 over the outside of the mouth of said carton; and a movable plunger adapted to cause said closure to assume an inclined position as it enters the carton mouth, substantially as described.

60 4. In a carton closing apparatus, the combination of means for cutting out a closure slightly larger than the carton to be closed; means for supporting the outer edge of the end of said carton; means for placing said 65 closure in said end in an inclined position;

and means of the same diameter as the interior of said carton for forcing said inclined closure to its final position, substantially as described.

5. In a carton closing apparatus, the combination of means for cutting out a closure slightly larger than the carton to be closed; means comprising a movable ring for supporting the outer edge of the end of said carton; means operated from said cutting means for moving said ring; means for placing said closure in said end in an inclined position; and means of the same diameter as the interior of said carton for forcing said inclined closure to its final position, substantially as described. 70 75 80

6. In a carton closing apparatus, the combination of a mandrel carrying a carton to be closed; means for cutting out a disk larger than the interior of said carton; means associated with said mandrel for causing said disk to enter said carton in an inclined position; means of the same diameter as said carton for forcing said disk home inside said carton; means for moving said mandrel, carton and disk to a crimping means; and means for spinning over the edge of said carton to hold said disk in place, substantially as described. 85 90 95

7. In a carton closing apparatus provided with a mandrel carrying a carton, and having means for causing said mandrel to move said carton successively opposite a disk closing means, opposite an edge crimping means, and opposite a groove forming means, in combination with means for cutting out a disk larger than said carton and forcing the same home in said carton; means for crimping over the edge of said carton to prevent the outward movement of said disk; and means for forming a groove in said carton in close proximity to said disk to prevent the latter from being forced inwardly, substantially as described. 100 105 110

8. In a carton closing apparatus provided with a mandrel and means to move said mandrel successively to different positions, the combination of means for forcing closures slightly larger than the interior of the cartons inside the latter; means for crimping over the edges of said cartons to hold said closures on one side against an outward movement; and means to form grooves in said cartons to hold said closures on the other side against an inward movement, substantially as described. 115 120 125

9. In a carton closing apparatus, the combination of a mandrel provided with a groove adapted to move a carton in a circular path; a crimping tool adapted to act on said carton; a grooving tool adapted to form a groove in said carton; and common means for rotating said mandrel and crimping tool, substantially as described. 126 130

10. The combination of a mandrel adapt-

ed to carry a carton having a concave end; a cutter plunger slightly larger in diameter than said mandrel; an expanding plunger adapted to expand to the size of said mandrel; and a plunger having a convex end coacting with said mandrel, substantially as described.

In testimony whereof, I affix my signature, in presence of two witnesses.

GEORGE W. BEADLE.
